SOUND RECORDING APPARATUS

Joseph L. Underhill, London, England, and Glenn L. Dimmick, Haddonfield, N. J., assignors to Radio Corporation of America, a corporation of Delaware

Application May 28, 1938, Serial No. 210,592

5 Claims. (Cl. 179—100.3)

This invention relates to an improved sound recording apparatus and more particularly to sound recording apparatus for variable density recording with ground noise reduction.

In Dimmick Patents Nos. 2,095,317 and 2,095,318, patented October 12, 1937, there are disclosed methods and apparatus for variable density sound recording by what is known as the "penumbra" method, wherein an opaque mask produces a graduated intensity in a beam of light and the beam of light is then vibrated across a plate having a slit so positioned as to select an appropriate portion of the beam which is thereafter directed onto the sensitive film.

In both of the aforesaid patents, ground noise reduction may be applied, and specific apparatus for that purpose is shown in Fig. 7 of the latter of the patents.

The present invention is an improvement on that of the said patents in that an improved method of and apparatus for ground noise reduction are provided.

It has been customary in the prior art to operate the noise reduction amplifier, both for variable width and variable density recording, so that the bias or shutter current from the ground noise reduction amplifier decreases as the modulation increases, reaching zero at some predetermined modulation level. The reason for this is that the zero current shutter position may be definitely fixed mechanically and forms an interchangeable end stop at maximum modulation. If the prior art systems were operated in the reverse direction, that is, if the noise reduction current were to rise with increased modulation, it would be difficult to suddenly limit the current at a predetermined and unchanging value.

The systems of the prior art had the disadvantage that the characteristic curve of the vacuum tube amplifiers usually becomes less and less linear as it approaches zero current, and it has heretofore been difficult for that reason to establish a definite end value of the shutter opening with increased modulation and at the same time to secure a linear response of the ground noise reduction mechanism in accordance with modulation.

In our improved apparatus for and method of ground noise reduction, we accomplish both of the foregoing desirable results simultaneously by increasing the bias current with increased modulation and providing optical means for determining the end position of the shutter movement.

One object of the invention is to provide an

improved method of and apparatus for ground noise reduction.

Another object is to provide an improved method of variable density recording.

5 Another object of the invention is to provide an improved type of ground noise reduction shutter.

Another object of the invention is to provide a recording system wherein ground noise reduction current increases as the modulation increases.

Another object of the invention is to provide a recording system wherein the ground noise reduction shutter response has linear relation to the amplitude of modulation.

Other and incidental objects of the invention will be apparent to those skilled in the art from a reading of the specification and the accompanying drawing, in which

Figure 1 is a perspective view of the improved recording optical system,

Figure 2 is a schematic wiring diagram of the apparatus,

Figure 3 shows the relation between the recording beam and the slit at the position of maximum modulation, and

Figure 4 shows the relation between the recording beam and the slit at the position of minimum modulation.

30 Referring first to Fig. 1, the usual exciter lamp 10 directs a beam of light past the penumbra mask 11—12, as in Patent 2,095,317, through the condenser lens 13, the aperture 15 in the aperture plate 14, and the lens 16 to the galvanometer mirror 17 which is adapted to be vibrated in accordance with the modulation currents passing through the coil 24. Light reflected from the mirror 17 is directed by the lens 18 to the slit plate 19, the lenses 16 and 18 together forming an image of the aperture 15 on the slit plate 19 in proper relation to the slit 20. Due to the effect of the mask 11, a beam of light graduated in intensity, as indicated at 21, is formed around the slit 20 in the plate 19 and the portion thereof passing through the slit 20 is focused by the lens 22 upon the film 23. As the mirror 17 is vibrated, the image 21 moves across the slit 20 and due to the corresponding variation in the light striking the film 23, a variable density record is produced thereon.

40 Referring now to Fig. 2, sound impulses from the microphone 26 are amplified by the amplifier 27 and transmitted to the galvanometer coil 24. A portion of the amplified sound impulses are transmitted to the amplifier-rectifier and fil-

ter 28 as shown and described, for example, in McDowell Patent 1,856,197, issued April 26, 1932, and the rectified currents, corresponding to the envelope of the sound waves, are transmitted to the shutter coil 25. This circuit differs from the 5 circuit of McDowell in that the connections of the unit 28 are reversed so that when the amplitude of the sound impulses from the amplifier 27 increase, the output from rectifier, the filter, and the variable current through the coil 25 10 increase.

When the current through the coil 25 increases, the shutter 11, Fig. 1, is moved downwardly, thereby causing light of greater intensity to strike the slit 20 at the same position of the beam. As shown in Fig. 4, when the mask 11 is in the zero current position with no modulation, the portion of the beam 21 of least intensity coincides with the slit 20 producing a minimum density on the record 23 and a correspondingly great density on a print thereof, with correspondingly low ground noise. When the shutter 11 is withdrawn, a portion of the beam 21 of intermediate intensity, i. e., 50% of maximum intensity, falls on the slit 20, as shown in Fig. 3, when the galvanometer mirror 17 is in the same position it would occupy if there were no modulation. Due to the fact that no current may flow through the coil 25 from the amplifier-rectifier and filter 28 over this range, the current may be so chosen as to fall on the linear portion of the characteristic curve of the vacuum tubes used, and a correspondingly linear response of the shutter 11 may be secured. Likewise, if the shutter 11 is so constructed mechanically or the magnet 25 is so constructed that the response of the shutter 11 is not linear with current through the magnet 25, then an appropriate portion of the characteristic curve of the output tubes of the unit 28 may be chosen to compensate for this lack of linearity and a response of the shutter 11 which is linear with input from the unit 27 to the unit 28 may be thereby secured.

In order to establish a definite end point to the effect of movement of the shutter 11, an auxiliary stop 12 may be provided. It will be apparent that when the upper edge of the shutter 11 is past the upper edge of the stop 12, no further effect is produced by further movement of the shutter 11. The variable intensity light beam remains fixed in the position shown in Fig. 3. Alternatively, a positive mechanical stop may be provided for the shutter 11 precluding its movement beyond a position corresponding to the position of the light stop 12. Further increase of current through the magnet does not produce any further deflection of the shutter 11.

It will be apparent that the alternative constructions referred to above provide a stop for the movement of this shutter, which stop is either optical, as shown in Fig. 1, or mechanical, both producing identical results in that the effective withdrawal of the penumbra mask is positively limited and cannot exceed a predetermined value on increase in ground noise reduction current.

It will be apparent to those skilled in the art

that our invention is not limited to the form shown in Fig. 1, but that, if desired, duplicate shutters may be used connected as shown and described and operated in opposition in the manner shown in Fig. 7 of Dimmick Patent No. 2,095,318, each of these shutters being provided with an appropriate stop either optical or mechanical.

It will also be apparent that the stops 11 and 12 do not need to be located between the lamp 10 and the lens 13. Either or both of these stops may be located, if desired, between lens 13 and lens 16, as shown in the aforesaid Patent No. 2,095,318. If desired, one of the stops may be located where shown and the other located between the lenses 13 and 16 so that the two stops are optically coincident, or the penumbras produced by the two stops at the slit plate 19 are of the same height.

We claim as our invention:

1. Sound recording apparatus including means for directing a beam of light in the form of a fine line upon a sensitive film, means for modulating said beam in accordance with sound impulses to be recorded, and means for modulating said beam substantially entirely in a linear relation to the envelope of the sound impulses to be recorded.

2. Sound recording apparatus including means for directing a beam of light to a slit, means for imaging light passing through said slit in the form of a fine line upon a sensitive surface, means for modulating said beam of light in accordance with sound impulses to be recorded, and means for further and simultaneously modulating said beam of light substantially entirely in a linear relation to the envelope of said sound impulses.

3. Sound recording apparatus including means for directing a beam of light to a slit, means for imaging light passing through said slit in the form of a fine line upon a sensitive surface, means for modulating said beam of light in accordance with sound impulses to be recorded, and shutter means for further and simultaneously modulating said beam of light substantially entirely in a linear relation to the envelope of said sound impulses.

4. Sound recording apparatus of the penumbra type, including a penumbra mask movable in accordance with the envelope of the sound waves to be recorded, a fixed stop located at a position corresponding to the maximum amplitude of the sound waves to be recorded, and means for moving said movable mask substantially entirely in direct linear relation to the envelope of sound impulses.

5. In sound recording apparatus of the penumbra type, a movable penumbra mask, means for moving said mask substantially entirely in linear accordance with the envelope of the sound waves to be recorded, and means for limiting the effective movement of said mask to correspond with the maximum amplitude of sound waves to be recorded.
